UNITED STATES PATENT OFFICE.

THOMAS F. QUINN, OF BROCKTON, MASSACHUSETTS.

GAME APPARATUS.

1,190,003.

Specification of Letters Patent.

Patented July 4, 1916.

Application filed December 30, 1914. Serial No. 879,766.

To all whom it may concern:

Be it known that I, THOMAS F. QUINN, a citizen of the United States, residing at Brockton, in the county of Plymouth and 5 State of Massachusetts, have invented certain new and useful Improvements in Game Apparatus; and I do hereby declare the following to be a full, clear, and exact description of the invention, such as will enable others skilled in the art to which it 10 pertains to make and use the same.

This invention relates to game apparatus, designed to simulate a football game, and one of the principal objects of the invention 15 is to provide a game which can be played indoors by two parties, and which will require considerable skill and knowledge of the football game in order to play it successfully, and which will be instructive in teaching 20 the game of football.

Another object of the invention is to provide a game apparatus which will be instructive, amusing, and entertaining to persons interested in the game of football.

25 The foregoing and other objects of the invention may be attained by means of the construction and devices illustrated in the accompanying drawing, in which

Figure 1 is a top plan view of a game 30 board, with game pieces thereon, said game pieces being lined up in position to play a game of football, and Fig. 2 is a side elevation of the men or accessories to the game.

Referring to the drawing the numeral 1 35 designates a square or rectangular board representing a football field, on the face of which are alternately arranged white and colored squares 2, which are intersected by horizontal lines 3 to indicate the yard lines.

40 On opposite sides of the board is a double series of numerals commencing at one side with the numeral 5, and progressively arranged opposite the lines 3, as 5, 10, 15, 20, and so on, to the center, 50 yard line. At 45 the two ends of the board are arranged a series of numerals extending across the board in the first line and indicated as 1, 2, 3 and 4, oppositely arranged, and the central square is numbered 6 to represent a 50 goal a.

The line man A, consisting of the center, guards, and tackles, are shown as having a knob upon the upper end and a dome-shape portion having a flat bottom to rest upon 55 the board and to be moved about like a checker. The men A¹ are each provided

with a surrounding bead 6 and a dome-shape cap 7, as shown in Fig. 2. The two half backs and one quarter back are also provided with the bead 6 and the dome- 60 shape top 7, while the full back A² is represented by a round checker having a concave portion 8 in the center thereof for the ball A³. The opposing men B, are of substantially the same contour as the men al- 65 ready described, but are provided with a cross mark 9 on the base portion thereof so as to distinguish them from the other men.

The rules for playing the game are as 70 follows:

1. The game is to be played with eleven (11) men on each side, five (5) line men, two (2) ends, and four (4) backs.

2. The five (5) line men can only move 75 or jump toward the opponent's goal. The backs can move or jump either way or both ways, excepting the back that carries the ball.

3. The man carrying the ball can only 80 move toward the opponent's goal and cannot jump either way.

4. The game begins with the eleven (11) winning the toss placing the five (5) line men and two (2) ends on the 50-yard line 85 in the center of the field and the four (4) backs must be placed as indicated in the drawing, with a full back carrying the ball.

5. The opposing eleven (11) are placed with the five (5) line men and two (2) 90 ends, ten yards directly opposite the other line and end men, and the four (4) backs being twenty yards or more from the opponent's line men, but may be placed in any position the player desires. 95

6. Either player must jump when he has a chance.

7. When a player jumps a man, it is to be removed from the board, as in the game of checkers. 100

8. The ball is considered downed when jumped or blocked, so that it cannot move forward any more. Then the opposite player has the ball and lines his men on the yard-line where the ball was downed and 105 places his backs in the position shown.

9. If the player first having the ball scores a goal or any of the points either side of the goal, his opponent has the ball and starts on the 50-yard line. 110

10. If the player first having the ball is downed on the 5-yard, 10-yard, 15-yard, or

20-yard line, the ball begins play on the 20-yard line with his opponent having the ball, or either player being downed, the opposite player has the ball.

5 11. A game is finished when each player has the ball twice, that is to say, four periods.

12. If each player has the ball twice and does not score, the game will be called 0 to 0, 10 or may be continued until someone scores. Each side must have the ball an equal number of times.

13. Six points are made when the ball is placed on the goal. Six, four, three, two, 15 and one points are made when the ball is placed in any of the squares either side of the goal.

14. The ball must always be in the center, or as near the center of the field as possible, 20 when lined up to begin playing.

From the foregoing it will be obvious that the game of football is closely followed in the game, and that the game will be instructive, amusing, and especially entertaining to 25 persons desiring to learn the game of football or to those who have a specific knowledge of the game.

Various changes may be made in the de-

tails of construction as to the shape of the men, the color indications, without departing from the spirit and scope of the invention as defined in the claim.

What is claimed is:—

A game apparatus consisting of a rectangular board representing a field, the upper face of which is provided with a plurality of alternatingly arranged white and colored squares, said squares being intersected by horizontal lines to indicate the yard lines, the opposite ends of said board being numbered to represent the score, two sets of colored pieces representing two foot ball teams and one piece of each set provided in its upper face with a recess and a ball seated in said recess to be carried by said piece, 45 each of said pieces adapted to be moved forwardly and certain of said pieces allowed to be moved forwardly or rearwardly to provide openings for the back piece carrying the ball, substantially as set forth.

50 In testimony whereof I affix my signature in presence of two witnesses.

THOMAS F. QUINN.
